Primary Examiner — Samantha Q Lawrence*Assistant Examiner* — Holly M Rodriguez(57) **CLAIM**

The ornamental design for a monitor wall mount apparatus, as shown and described.

DESCRIPTION

FIG. 1 is a front perspective view of the monitor wall mount apparatus;

FIG. 2 is a front elevational view of the monitor wall mount apparatus;

FIG. 3 is a rear elevational view of the monitor wall mount apparatus;

FIG. 4 is a left side elevational view of the monitor wall mount apparatus;

FIG. 5 is a right side elevational view of the monitor wall mount apparatus;

FIG. 6 is a top plan view of the monitor wall mount apparatus; and,

FIG. 7 is a bottom plan view of the monitor wall mount apparatus.

The three interlocking diamonds shown in broken lines forming no part of the claimed design is a registered trademark of PERLESMITH. The other broken lines in the drawings depict portions of the monitor wall mount apparatus that form no part of the claimed design.
